UNITED STATES PATENT OFFICE.

CONRAD HARRELL, OF WHIGHAM, GEORGIA.

TRACE-CARRIER.

SPECIFICATION forming part of Letters Patent No. 696,332, dated March 25, 1902.

Application filed December 5, 1901. Serial No. 84,732. (No model.)

To all whom it may concern:

Be it known that I, CONRAD HARRELL, a citizen of the United States, residing at Whigham, in the county of Decatur and State of Georgia, have invented certain new and useful Improvements in Trace-Carriers; and I do declare the following to be a full, clear, and exact description of the invention, such as will enable others skilled in the art to which it applies to make and use the same.

The invention relates to trace-carriers, and more particularly to that class of devices adapted to be attached to the ends of a back-band used on plowing-harness and designed to support the trace at various distances above the ground, whereby the depth of insertion or working of the plow may be controlled.

The object of the invention is to provide a device of this character which shall be simple of construction, durable in use, comparatively inexpensive of production, and which is constructed to guide the lines as well as to support the trace-chains.

With this object in view the invention consists of certain novel features of construction, combination, and arrangement of parts, which will be hereinafter more fully described, and particularly pointed out in the appended claim.

In the accompanying drawings, Figure 1 is a view of a portion of a back-band, illustrating the application thereto of my improved trace-carrier; and Fig. 2 is a longitudinal vertical sectional view through the same parts, showing the trace-chain in position.

Referring to the drawings, 1 denotes the lower end of the back-band, to which is secured my improved trace-carrier.

The trace-carrier consists of a plate 2, which is riveted or otherwise secured to the back-band and has struck up from it hooks 3, the bills 4 of which are arranged in vertical parallel order and project equidistant from the plate.

5 denotes a latch pivoted to a cross-bar 6, formed integral or secured to the lower end of the plate and provided at its upper end with a cylindrical bolt-casing 7, within which is arranged a bolt 8, forced upwardly by a coil-

spring 9. This bolt-casing is provided with a longitudinal slot 10, through which projects a knob 11, by means of which the bolt may be retracted. The latch and bolt-casing are adapted when the device is in operative position to bridge over the hooks, as shown in the drawings, and the bolt is adapted to project through an aperture 12, formed in a housing 13, secured at the upper end of the plate, in which housing is arranged a pulley 14 to serve as a guide or support for the line or rein.

15 denotes a cross-bar arranged at the lower end of the plate and to which may be attached a girth when occasion requires.

In operation one of the links of the trace-chain is engaged with one of the hooks, according to the depth it is desired to work the plow, and the latch swung upwardly and its bolt locked to the housing. When the latch is in this position, it will be absolutely impossible for the trace-chain to become detached or to shift from one hook to the other. When it is desired to adjust the chain to a hook above or a hook below that to which it was formerly connected, this may be quickly done by retracting the bolt, swinging the latch downwardly, and hooking the link of the chain over the hook to which it is desired to attach it, and then locking the latch in its former position, as above explained.

From the foregoing description, taken in connection with the accompanying drawings, the construction, mode of operation, and advantages of the invention will be readily understood without requiring a more extended explanation.

Various changes in the form, proportion, and details of construction may be made within the scope of the invention without departing from the spirit or sacrificing any of the advantages thereof.

Having thus described my invention, what I claim, and desire to secure by Letters Patent, is—

A trace-carrier of the character described, consisting of a plate from which are struck up hooks arranged in vertical parallel order, the bills of which project upwardly and are equidistant from the plate, a housing secured

to said plate at its upper end and formed with a hole to serve as a bolt-keeper, a sheave journaled in said housing, a latch hinged to said plate and adapted to bridge said hooks, and a spring-actuated bolt carried by said latch and adapted to engage the hole in the housing and retain the latch in engagement with the hooks, substantially as set forth.

In testimony whereof I have hereunto set my hand in presence of two subscribing witnesses.

CONRAD HARRELL.
